CORSET-CLOSURE.

1,089,158.

Specification of Letters Patent.

Patented Mar. 3, 1914.

Application filed January 22, 1913. Serial No. 743,533.

To all whom it may concern:

Be it known that I, ISIDOR ROTH, a citizen of the United States, residing at Bridgeport, county of Fairfield, State of Connecticut, have invented an Improvement in Corset-Closures, (Case B,) of which the following is a specification.

This invention has for its object to provide a lace front maternity corset in which lacing hooks shall be substituted for eyelets and in which the back may be wholly closed if preferred, which shall be yielding and comfortable to wear, and will not press strongly on any portion of the figure.

With these and other objects in view I have devised the novel maternity corset which I will now describe referring to the accompanying drawing forming a part of this specification and using reference characters to indicate the several parts.

Figure 1 is a front view showing the corset in position on the figure of the wearer; Fig. 2 a similar view of the corset as seen from the back; Fig. 3 a detail view on an enlarged scale, partly broken away, showing the supplemental protecting bone or steel lying parallel with the hook supporting steel, but in a separate pocket, and Fig. 4 is a section on an enlarged scale on the line 4—4 in Fig. 1, looking in the direction of the arrow.

My novel corset comprises a back section 10, extending across from side to side of the corset. I have shown this back section as entirely closed. It may, however, be partly open if preferred or the corset may be made in two halves, these details of construction being wholly immaterial so far as the present invention is concerned. Next to the back section, which is non-elastic, are non-elastic side sections 11 which are adjustably secured to the back section by lacings 12 engaging eyelets in the sections. Next to the side sections and secured thereto by seams 13 are elastic front sections 14 which are made relatively wide at the bottom and narrow toward the top and are secured to the hook members 15 by seams 16. The hook members are provided with outer pockets 17 and inner pockets 18. Pockets 18 receive steels 19 and strips of tape, indicated by 20, which overlie steels 19 and carry the hooks 21, the tape strips being secured by seams 22. The front of the corset is ad-

justably closed by lacings 23 and 24 which preferably start at about the waist-line, lacing 23 starting from eyelets 25 and extending upward and lacing 24 starting from eyelets 26 and extending downward. In putting on the corset one of the lacings may be tied at the waist-line, then the ends of the other lacing crossed and engaged with the hooks and tied at the top or bottom, as may be, and then the first mentioned lacing is untied, crossed and engaged with the hooks and tied at the other extremity of the corset. In order to cover the undervest of the wearer between the hook members, I provide the outside pockets 17 in which supplemental protecting bones or steels 27 are placed. These supplemental protecting bones act to prevent the undervest from rolling up between the contiguous edges of the hook members, and lie between the lacings and the undervest, preventing the lacings from cutting into the flesh.

The operation will be readily understood from the drawing. The front lacings enable the wearer to quickly and conveniently tighten or loosen the corset, as may be required. When the corset is put on one lacing may be tied at the waist-line to retain the corset in place and the other lacing engaged with the hooks and tied and then the first mentioned lacing is untied, engaged with the hooks and tied at the other extremity of the corset. The supplemental protecting bones cover the undervest between the hook members and render it impossible for the undervest to roll up or for the lacings to incommod the wearer, and the elastic front sections yield as may be required and insure comfort and freedom of movement.

Having thus described my invention I claim:

1. A corset of the character described having at the front hook members each provided with inner and outer pockets, hook supporting steels underlying tape strips carrying hooks in the inner pockets and supplemental protecting bones in the outer pockets, and lacings engaging the hooks and passing over the supplemental bones to protect the wearer.

2. A corset of the character described including front sections having hook members connected to the front sections each pro-

vided with inner and outer pockets, hook supporting steels underlying tape strips carrying hooks in the inner pockets and supplemental protecting bones in the outer 5 pockets, the hook members each provided with a pair of eyelets at the waist line between the inner pockets and adjacent front sections, and lacings passing through the eyelets extending in the opposite direction,

passing over the protecting bones, and en- 10 gaging the hooks.

In testimony whereof I affix my signature in presence of two witnesses.

ISIDOR ROTH.
